[57] CLAIM

The ornamental design for a door-mounted hanger holder, as shown and described.

DESCRIPTION

FIG. 1 is a top, front, and left side perspective view of a door-mounted hanger holder showing our new design, with the front in an opened position;
FIG. 2 is an enlarged front elevational view thereof;
FIG. 3 is an enlarged rear elevational view thereof;
FIG. 4 is an enlarged left side elevational view thereof;
FIG. 5 is an enlarged right side elevational view thereof;
FIG. 6 is an enlarged top plan view thereof; and,
FIG. 7 is an enlarged bottom plan view thereof.

FIG. 1

FIG. 4

FIG. 2

FIG. 5

FIG. 3
